COMBINATION BOX SPRING AND MATTRESS

Earl E. Roher, Hutchinson, Kans.

Application March 28, 1950, Serial No. 152,430

2 Claims. (Cl. 5—351)

1

This invention relates to beds and bedding, and has particular reference to a novel and improved one-piece combination box spring and mattress.

The primary object of this invention is to provide a novel combination of an innerspring mattress and box spring, wherein these components of the unit are so constructed and arranged with respect to each other that they require substantially less ticking, filling, cord and padding than required by conventional mattress and spring constructions, yet the combination unit nevertheless provides comfort and wearing qualities superior to those afforded by beds of conventional construction.

It is a further object of the invention to provide an improved spring and mattress combination for a bed, wherein the mattress and spring are of neater appearance than those heretofore used, yet at the same time are so arranged that they may be more conveniently aired and more easily kept clean.

These objects are accomplished, according to the present teaching, by providing a combination box spring and innerspring mattress constructed as a single integral unit, so that the box spring and the mattress are securely held to each other in fixed relative positions, yet are separated by a semi-permanent insulation member such as a sisal pad, so that the springs of the mattress and spring unit may function independently to give the greatest resiliency and comfort to the unit.

In the preferred form of the invention, the combination box spring and mattress unit is provided with a detachable cover in the nature of a thin, quilted pad closely fitted to the mattress and having ties to hold it in position thereon, but provided with a zipper closure at one corner to facilitate removal of the pad when required.

The present preferred embodiment of the invention is illustrated in the drawings of this specification,

Figure 1 is a perspective view of the combination box spring and mattress construction with the detachable pad covering in place; and

Figure 2 is a cross sectional view through the combination unit.

The unit comprises, in general, a lower or box spring portion generally designated as 10, together with an upper mattress portion 11 over which the detachable cover 12 is fitted. The box spring unit 10 is arranged to rest directly on the frame members 13 of the bed, which may have legs 14 of any conventional type. The box spring unit includes a multiplicity of helical coil springs 15 which rest on cross supports 16 and extend up-

2

wardly to a semi-permanent insulation member such as the sisal pad 17. The springs 15 may be secured to each other and to the members 16 and 17 by any conventional means such as the tie cords, metal clips or wire indicated at 34, ordinarily used for the purpose. The underside of the unit is closed by a dust cloth 18, and a similar cloth or ticking 19 is extended downwardly from the edges of the insulation member 17 to close the sides of the box spring unit and give it a neat, clean and finished appearance.

The mattress unit, generally designated as 11, includes a multiplicity of coil springs 21 extending upwardly from the sisal insulation member 17 to an underlayer 22 of ticking on the top pad 23 of the mattress. This top pad may be tufted in the usual manner by tie cords 24 extending from the ticking 22 up through the top fabric 25 of the mattress. In the form of the mattress shown, the springs 21 are equally spaced and positioned directly above the springs 15 of the box spring unit, but it will be understood that it is not necessary that this be done since the springs are physically separated by the sisal pad 17, so that each set of springs functions independently of the other. Thus, if desired, the innerspring mattress unit may be provided with a larger number of relatively smaller springs according to the usual practice in the bedding arts. In any event, the springs 21 of the box spring unit are held together and secured to the other parts of the mattress in any conventional way, as by the tie cords, wires or fabric pockets conventionally employed. The top pad 23 of the mattress extends downwardly in a skirt portion 26 and is covered at its edges by an outer fabric layer 27, the lower end of which is joined to the upper edge of the fabric 19 to completely close the outer edges of the unit so that it will present a clean, attractive and unitary appearance.

The mattress unit is covered by a detachable pad covering 28 which extends over the entire area of the mattress and has downwardly depending side portions 29 at its marginal edges. As illustrated, these side portions or skirts extend downwardly to a point just below the lower edge of the mattress fabric 27 and are provided with tie cords 30 and small coil springs 31 securing them to anchor tabs 32 on the lower edge of the box spring unit. The skirt 29 may also be provided with a zipper closure 33 at one corner (Figure 2). The pad covering 28 is preferably provided with a water repellent layer on its bottom side and, if desired, may have elastic sections

at the corners so that it will fit the mattress snugly and neatly, yet may be removed with ease.

From the foregoing, it will be seen that the applicant, by the present teachings, has provided a novel and improved bedding unit so designed as to provide comfort and wearing qualities equal or superior to those afforded by conventional bedding constructions, yet accomplishing this important object with a construction requiring less ticking, padding and cordage. The entire bed is of neat, unitary appearance, and since the parts are all firmly secured to each other, there is no possibility for relative shifting of the spring and mattress as occurs with prior types of spring and mattress constructions. The utility of the invention is still further increased by the use of the detachable, pad covering which protects the surface of the mattress, so that it increases the wearing qualities of the unit and also covers and pads the tufted top surface of the mattress so that the presence of the tufts will not be detected. In addition to this, it will be seen that the detachable pad covering provides a place under the edges of the pad covering skirt in which to tuck sheets and bed covers, so that the bed may be made up with a neater and more trim appearance than by conventional bedding methods. At the same time, the detachable nature of the pad covering facilitates removal as required, so that both the pad covering and the combination spring and mattress unit may be easily cleaned, aired and renovated.

Having thus described my invention, what I claim as new and desire to secure by United States Letters Patent is:

1. As an article of manufacture, a combination bedding unit comprising a box spring section, a mattress section and a coacting pad covering; the box spring section comprising a rigid bottom frame with a multiplicity of helical coil springs secured thereto and extending upwardly therefrom; with a horizontal insulation member comprising a sisal pad secured to the upper ends of said coil springs; the marginal edges of said sisal pad being vertically yieldable with respect to the bottom frame and joined thereto solely by flexible fabric ticking, extending vertically between said pad and said frame and closing the sides of the box spring unit; the mattress unit comprising a multiplicity of helical coil springs secured to the upper side of the sisal pad and extending upwardly therefrom, with a horizontal top pad of the mattress secured to and supported on the upper ends of said springs; said top pad having a marginal skirt extending downwardly around the outer edge of the mattress portion and joined to the upper edge of the aforementioned fabric ticking, whereby said pad and ticking coact to completely close the marginal edges of the bedding unit and present an attractive and unitary appearance; a detachable pad covering comprising a horizontal portion coextensive with the mattress pad and having side portions extending downwardly alongside the skirt portion of the mattress pad, said side portions terminating at a

point between the mattress and box spring sections and enclosing the mattress snugly, whereby sheets and bed covers may be held against displacement by tucking them under the edges of said side portions and spaced elastic means connecting the side portions of said detachable pad to said bottom frame.

2. As an article of manufacture, a combination bedding unit comprising a box spring section and a mattress section and a coacting pad covering; the box spring section comprising a rigid bottom frame with a multiplicity of helical coil springs secured thereto and extending upwardly therefrom, with a horizontal insulation member comprising a sisal pad secured to the upper ends of said coil springs; the marginal edges of said sisal pad being vertically yieldable with respect to the bottom frame and joined thereto solely by flexible fabric ticking extending vertically between said pad and said frame and closing the sides of the box spring unit; the mattress unit comprising a multiplicity of helical coil springs secured to the upper side of the sisal pad and extending upwardly therefrom with a horizontal top pad of the mattress secured to and supported on the upper ends of said springs; said top pad having a marginal skirt extending downwardly around the outer edge of the mattress portion and joined to the upper edge of the aforementioned fabric ticking, whereby said pad and ticking coact to completely close the marginal edges of the bedding unit and present an attractive and unitary appearance; said detachable pad covering comprising a horizontal portion coextensive with the mattress pad and provided with side portions extending downwardly alongside of and parallel to, the skirt portion of the mattress pad, the said side portions terminating at a point between the mattress and box spring sections and enclosing the mattress; whereby sheets and bed covers may be held against displacement by tucking them under the edges of the detachable pad covering side portions and the side portions of the mattress, and a plurality of spaced means connecting the side portions of the detachable pad covering to said bottom frame, said last named means including coil springs connecting the side portions of said pad covering to said bottom frame.

EARL E. ROHER.
